UNITED STATES PATENT OFFICE

CHARLES B. COATES, OF CLEVELAND, OHIO, ASSIGNOR TO CHICAGO PNEUMATIC TOOL COMPANY, OF NEW YORK, N. Y., A CORPORATION OF NEW JERSEY

SHOCK ABSORBING HANDLE

Application filed February 13, 1928. Serial No. 253,804.

This invention relates to power tools of the portable or hand-operated type, and particularly to the handles by which such tools are supported. More specifically it concerns 5 handle attachments for power tools used for stud setting, nut running, screw driving and similar operations.

A principal object of the invention is to relieve the operator of such a tool of at least 10 a part of the sever shock or recoil which he experiences when the securing member is driven home and the torque of the tool is transmitted back to the operator. Other objects will be apparent from the detailed description, which follows:

In order to illustrate the invention, concrete embodiments thereof are shown in the accompanying drawing in which:

Fig. 1 is a plan view of a power tool 20 equipped with the improved handle;

Fig. 2 is a sectional view substantially on the line 2—2 of Fig. 1;

Fig. 3 is a plan view on a reduced scale of a modification; and

Fig. 4 is a side elevational view on a reduced scale of the tool shown in Fig. 1.

In the chosen embodiments of the invention a portable power tool, having a motor (not shown) operated from any suitable 30 source of power such as fluid pressure or electricity, is diagrammatically indicated at A. Its rotatable spindle α is indicated as offset from the central axis of the tool. The manual supporting means shown in Fig. 1 comprise an elongate substantially flat strip 3 of resilient material such as spring metal. The central portion 3a of the strip is bent into a substantially U-shaped form and is secured in flat engagement with the casing of tool A

40 by suitable means such as cap screws 4. The ends of spring member 3 are divergently return bent beyond the U-shaped central portion to dispose the free ends thereof in substantial alignment upon opposite sides of tool A, the ends having grips secured thereto which may take the form of plates 5 generally semicircular in cross section (Fig. 2) and secured upon opposite sides of strip 3 by suitable means such as rivets 6. The resiliency of handle strip 3 at the central U-shaped

portion 3a may be reduced if desired in any suitable manner; the strip may be thicker at this point, or may be ribbed, or may have a stiffening member 7 of suitable shape clamped thereagainst. The divergently and outwardly bent portions of handle strip 3, adjacent grips 5, are of sufficient resiliency to absorb wholly or in part the reaction of the drill which results when the spindle α is suddenly stopped or retarded thereby relieving 60 the operator of shock. With the spindle turning in the direction indicated by the small arrow, the reaction of tool A will be in the opposite direction as indicated by the large arrow. To enable the operator better 65 to direct and control the tool the U-shaped portion handle member 3 is by preference secured to the tool on the side closest to the axis of the offset spindle as indicated in Fig. 1.

In the modification shown in Fig. 3 the 70 spring strip 3' is of greater length and the U-shaped central portion secured to the tool is made somewhat irregular by reverse return bends at 9 and 10 to give the grip portions 5' a greater degree of resiliency relative to tool A than is possible with the form shown in Fig. 1. The central portion of the strip 3' may be suitably stiffened if desired as indicated at 7'.

It is obvious that two handles secured to 80 the same spring strip need not be used unless desired. At times the operator of a tool supports and directs the same with one hand on a spade handle at the top of the tool and the other upon a side handle. 85 In such a case only one side of the shock absorbing handle would be used and the other side could be omitted entirely.

While the invention has been herein disclosed in what are now considered to be preferred forms, it is to be understood that minor changes and variations may be made therein without departing from the spirit and scope of the invention as set forth in the appended claims.

I claim as my invention:

1. The combination with a portable device having a rotatable spindle, of a flat spring member having free ends secured to said device at its central portion and having bends 100

disposing at its free ends in alignment on opposite sides of said device, said free ends providing handles for supporting said device.

2. The combination with a portable device
5 having a rotatable spindle, of a flat spring member stiffened at its central portion and having free ends, said central portion being fastened to said device, said member having bends to dispose said free ends on opposite
10 sides of said device, said free ends providing grip portions yieldably relative to said device in a plane transverse to the axis of said spindle.

3. The combination with a portable power
15 tool having a rotatable spindle, of a flat spring member formed with a substantially U-shaped central portion secured to said tool and disposing its ends in alignment on opposite sides of said tool, said ends forming
20 handles for manually supporting said tool and yieldably to absorb the reaction of the tool when the spindle is suddenly stopped.

4. The combination with a portable power
25 tool having a rotatable spindle, of an elongate member of flat spring material having a generally U-shaped central portion secured in flat face engagement with said tool, said portion being stiffened relative to the rest of
30 said member, grip members on the free ends of said member and disposed in axial alignment on opposite sides of said tool, the parts of said member between said central portion and said grip members being sufficiently
35 resilient to absorb at least a part of the reaction of the tool when the spindle is suddenly stopped or retarded by the work.

5. A handle unit for portable power tools comprising an elongate piece of flat spring metal having a bent and stiffened central
40 portion to be secured to the tool and having outwardly bent aligned ends provided with
45 grips, the bent portions of said piece adjacent said grips permitting yielding movement of the latter relative to said central portion.

6. A handle for portable power tools comprising an elongate piece of flat spring metal having a central portion to be secured to the tool and free ends adapted to be grasped, said piece having bends intermediate said free ends and said central portion to add resiliency to said piece and to dispose said free ends in substantial alignment.

7. A handle unit for portable power tools comprising an elongate piece of flat spring metal having a central portion to be secured to the tool and free ends adapted to be grasped, said piece having reverse return bends intermediate said free ends and said central portion to add resiliency to said piece and to dispose said free ends in substantial alignment but offset relative to said central portion.

8. A handle unit for portable power tools comprising an elongate piece of flat spring

metal having a central portion to be secured to the tool and having aligned ends provided with grips arranged to be disposed on opposite sides of the tool, the portions of the piece between the grips and the central portion having reverse return bends to give a high degree of resiliency.

Signed by me at Cleveland, in the county of Cuyahoga and State of Ohio this 8th day of February, 1928.

CHARLES B. COATES.
